UNITED STATES PATENT OFFICE.

JOSEPH PETRONE, OF NEW YORK, N. Y.

DESIGN FOR A HEEL FOR BOOTS OR SHOES.

SPECIFICATION forming part of Design No. 33,181, dated September 11, 1900.

Application filed August 16, 1900. Serial No. 27,113. Term of patent 7 years.

To all whom it may concern:

Be it known that I, JOSEPH PETRONE, a citizen of the United States, residing at the city of New York, borough of Manhattan, in the county and State of New York, have invented and produced a new and original Design for a Heel for Boots and Shoes, of which the following is a specification.

Reference is to be had to the accompanying drawings, in which—

Figure 1 is a side elevation of a heel embodying my design, and Fig. 2 is a sectional plan thereof on line 2 2 of Fig. 1.

The leading feature of my design consists in a heel for boots and shoes of elongated shape in cross-section and having its rear edge curved in its upper part according to a convex line inclined forwardly from top to bottom and in its lower part according to a concave line inclined rearwardly from top to bottom, the side and rear surfaces of the heel having ribs extending from top to bottom and conforming to the curvature of the heel.

As shown in the drawings, the front face A

of the heel is plane and the side surfaces A' and rear surface A² are curved in such a manner that the rear edge in its upper part A³ is convex and inclined forwardly from top to bottom, while in its lower part A⁴ it is concave and inclined rearwardly from top to bottom. The top and bottom surfaces of the heel are plane, as indicated by the straight lines A⁵ A⁶. The side surfaces A' and rear surface A² appear having rounded ribs or flutes A⁷ extending from top to bottom and following the curvature of the heel, as shown.

Having described my invention, what I claim as new, and desire to secure by Letters Patent, is—

The design for a heel for boots and shoes, substantially as shown and described.

In testimony whereof I have signed my name to this specification in the presence of two subscribing witnesses.

JOSEPH PETRONE.

Witnesses:

WILLIAM S. BENNET,
GEORGIA WILDER.
